PORTABLE SELF-LOCKING CLAMP

Ralph K. Coffman, Arlington County, Va.

Application August 21, 1945, Serial No. 611,768

3 Claims. (Cl. 144—303)

1

The object of the invention is to provide a clamp particularly adapted to light work and set in clamping position by mere pressure from the hands of the operator when it will automatically retain such set position; to provide a device of the kind indicated in which the pressure to be attained, whether it be great or slight, can be determined by the proper selection of the members of which the slide connecting the jaws is composed; and to provide a clamp which is of simple construction by reason of consisting of few parts and which is, therefore, susceptible of cheap manufacture.

With this object in view the invention consists of a construction and combination of parts of which preferred embodiments are illustrated in the accompanying drawings in which—

Figure 1 is a perspective view of one form of the invention;

Figure 2 is a vertical sectional view of the structure of Figure 1 in the plane of the axes of the members composing the slide;

Figure 3 is a perspective view similar to Figure 1 but showing a modification in which both jaws are movable with respect to the slide; and

Figure 4 is an elevational view of the invention in operative position with a work piece engaged by the jaws.

The jaws 10 and 11 are complemental and relatively movable, but one only is movable with respect to the slide 12 in that form of the invention shown in Figure 1, while both are adjustable along the slide when the invention follows the construction illustrated in Figure 3.

The slide is composed of the members or rods 12a, 12b and 12c arranged in parallelism and spaced a distance at least equal to the diameter of the members. If the invention be constructed as disclosed in Figures 1, 2 and 4, the members 12a etc. are terminally fixed in sockets opening on the inner face of the jaw 11, thus fixing the position of that jaw with respect to the slide. The jaw 10, however, must be movable along the slide and it is, therefore, provided with body holes for the members of the slide, the holes extending through the jaw from the inner face.

Since the locking function of the movable jaw is accomplished by firm frictional engagement with the members of the slide, it is necessary to flex the latter in the clamping operation. The jaws normally, therefore, are positioned at acute angles to the slide and are so arranged that their inner faces lie in converging planes, the noses or work engaging ends occupying the closest posi-

tions relatively and being provided with yielding grip mats 14 to prevent marring the engaged work piece.

In the use of the clamp the work piece—for example, the blocks 15 and 16 to which glue has been applied—is interposed between the jaws and they are brought into clamping position by the application of hand pressure at the heel ends. As the jaws are moved into parallelism, the intervening portion of the slide is flexed, the slide members being bowed, as illustrated in Figure 4. This bowing of the members of the slide disaligns their axes and the axes of the holes in the movable jaw with the result that the said jaw is frictionally retained in its clamping position.

At the free end in the construction shown in Figure 1 and at either end in the construction shown in Figure 3, the slide is provided with a bridging element 13. This element has the same angular position relative to the slide that the adjacent jaw occupies. The bridging element acts not only as a stop to prevent accidental removal of the jaw from the slide but it retains the members thereof in their parallel relation. But bowing of the slide can not be effected successfully to secure the movable jaw in clamping position if the bridging element be fixed to all the slide members. It is, therefore, fixed to only one, the center member 12b, in a socket of the element, the ends of the other members sliding in properly spaced similar sockets therein. By reason of this construction the bowing of the slide members is possible without destroying their uniformity of spacing.

While the use of the construction shown in Figure 3 requires the duplication of the bridging element, a certain advantage inures to that construction in that with it the clamping operation can be effected at varied points along the slide thus making more remote the time when the slide members will become permanently flexed by continued use and require renewal or reversal by rotating them one hundred eighty degrees from their original positions relative to each other and the jaws.

The pressure to be attained with the clamp determines the cross-sectional area of the members of which the slide is composed, the greater the cross-section the greater the pressure possible.

The invention having been described, what is claimed as new and useful is:

1. A clamp comprising co-operating jaws normally disposed with their complemental faces in

converging planes, and a slide on which the jaws are mounted and including a plurality of spaced resilient rods arranged in parallelism, at least one of the jaws having body holes through which the rods pass, the relative diameters of the rods and holes being such that the jaw may move freely along the rods when the latter are straight but will frictionally bind on the same when both jaws are forced into parallel clamping engagement with an interposed work piece and the rods are flexed in consequence. 10

2. A clamp comprising co-operating jaws normally disposed with their complementary faces in converging planes, a slide on which the jaws are mounted and including a plurality of spaced 15 resilient rods arranged in parallelism, at least one of the jaws having body holes through which the rods pass, the relative diameters of the rods and holes being such that the jaw may move freely along the rods when the latter are straight but will frictionally bind on the same when both jaws are forced into parallel clamping engagement with an interposed work piece and the rods are flexed in consequence, and a bridging member 20 spanning the rods at their extremities and fixed with respect to at least one but slidably with respect to the others. 25

3. A clamp comprising co-operating jaws, and

a resilient slide on which the jaws are mounted, at least one of the jaws having a guide axially aligned with and affording a running engagement with the slide, the jaws being normally disposed in converging planes, so that when spread into parallelism for engagement with an interposed work piece, the guide and slide are disaligned thereby binding the sliding jaw and flexing the slide. 5
